(57) **CLAIM**

The ornamental design for a gas distribution plate, substantially as shown and described.

DESCRIPTION

FIG. 1 is a top-front isometric view of a gas distribution plate according to a first embodiment;

FIG. 2 is a top-rear isometric view of the gas distribution plate of FIG. 1;

FIG. 3 is a front view of the gas distribution plate of FIG. 1;

FIG. 4 is a rear view of the gas distribution plate of FIG. 1;

FIG. 5 is a left side view of the gas distribution plate of FIG. 1;

FIG. 6 is a right side view of the gas distribution plate of FIG. 1;

FIG. 7 is a top view of the gas distribution plate of FIG. 1;

FIG. 8 is a bottom view of the gas distribution plate of FIG. 1;

FIG. 9 is a top-rear isometric view of a gas distribution plate according to a second embodiment, the front, left, right, top and bottom views are the same as the first embodiment; and, FIG. 10 is a rear view of the gas distribution plate of FIG. 9.
